(57) **CLAIM**

The ornamental design for a communication robot, as shown and described.

DESCRIPTION

FIG. 1 is a front, top and right side perspective view of a communication robot according to the design;
FIG. 2 is a front elevational view thereof;
FIG. 3 is a right side elevational view thereof;
FIG. 4 is a left side elevational view thereof;
FIG. 5 is a rear elevational view thereof;
FIG. 6 is a top plan view thereof;
FIG. 7 is a bottom plan view thereof; and,
FIG. 8 is a cross-sectional view taken along line **8-8** of FIG. 2.

The broken lines are for illustrative purposes only and form no part of the claimed design.

The hatching shown in FIG. 8 represents unclaimed subject matter and form no part of the claimed design.
